ANTI-DUST DEVICE FOR GRAIN ELEVATORS

John H. Arndt, St. James, Manitoba, Canada

Application August 8, 1957, Serial No. 677,058

3 Claims. (Cl. 209—147)

In the operation of a grain elevator, the grain is delivered to a pit hopper at the bottom of the elevator and from there it is elevated, by buckets on an endless belt, to a head box in the cupola or top of the elevator. The grain then passes from this head box, down a girber spout which is swingable to connect with any one of a series of spout openings on the cupola floor, said spout openings delivering to the various grain bins of the elevator. The belt and buckets pass up a tubular rectangular-shaped front leg from the pit hopper and return down a similar back leg.

As the buckets pass over a head pulley in the head box for their return passage, the grain is thrown or pitched out toward the entrance to the girber spout and accordingly, clouds of grain dust fills the head box. Most of this dust passes down the back leg with the down moving empty buckets and into the pit hopper from where it passes to all parts of the elevator and collects on various shelves, ledges and walls, forming a dangerous fire hazard, besides the health hazard to those working in the elevator.

The principal object of the present invention is to provide a fan between the cupola and the head box for positively removing the grain dust from said head box and delivering same to exterior atmosphere, and so materially reducing the above mentioned fire and health hazards in the elevator.

A further object of the invention is to accomplish the above, and at the same time, reduce the expense of same, by utilizing the bucket driving head pulley as the fan for the purpose, and making suitable changes to the existing structure of the head box.

A still further object of the invention is to make the above alterations in a simple, economical, efficient and durable manner, and such that the change over can be accomplished by an unskilled workman with a reasonable working knowledge of tools.

With the above important and other minor objects in view, which will become more apparent as the description proceeds, the invention consists essentially in the arrangement, construction and alterations of the parts hereinafter more particularly described, reference being had to the accompanying drawings in which:

Figure 1 is a partial vertical section through the cupola of an elevator, showing the grain elevating operational parts, and including changes made therein for the purpose of this invention.

Figure 2 is an enlarged horizontal sectional view taken on the line 2—2, Figure 1.

Figure 3 is an enlarged side view of approximately one half of the head pulley by itself, and with fan blades installed therein.

Figure 4 is an enlarged horizontal sectional view taken on the line 4—4, Figure 3.

Figure 5 is an enlarged prospective view of one of the attachable fan blades for the head pulley.

Figure 6 is an enlarged perspective view of one of the fastening plates for the fan blades.

2

In the drawings like characters of reference indicate corresponding parts in the several figures.

One end of the cupola of a grain elevator is shown in Figure 1 and comprises a roof 10, an end wall 11 and cupola floor 12 through which spouts 13 pass down to the various bins of the elevator (not shown). A pair of spaced bridgetrees 14 and 15 extend from the end wall 11 at an elevated position above the cupola floor and their outer ends are supported by a cross beam 16 which extends completely across the cupola (not shown). A closed head box 17 is supported between the bridgetrees and is provided with a pair of tubular legs 18 and 19 of rectangular cross section which pass down to a pit hopper (not shown) at the bottom of the elevator. The bottom of the head box 20, between the legs 18 and 19, slopes sharply toward the front leg 18 while the bottom 21, to the rear of that 20, slopes to a swingable girber spout 22 mounted thereon. This girber spout is adapted to be swung over, or be connected to, the various spouts 13 by suitable control mechanism (not shown).

A motor 23 is mounted on the front leg 18, and through a V-belt 24, drives a V-pulley 25 on one end of a shaft 26 which is journaled at 27 across the bridgetrees, in front of the head box. The opposite end of the shaft 26 is provided with a sprocket 28 which, through a chain 29, drives a larger sprocket 30 on one end of a shaft 31. The latter shaft is journaled at 32 on the bridgetrees and extends across and through the head box 17. Further, this shaft, within the head box, carries a wide rimmed head pulley 33 which drives an endless belt 34 through the lower front and back legs 18 and 19 to the pit hopper (not shown). The belt 34 carries a continuous line of spaced triangular grain buckets 35 which are adapted, when belt operated, to pick up and elevate grain from said pit hopper to the head box.

A rectangular-shaped opening 36 is provided on either side of the head box around the shaft 31 and above the bridgetrees. Battens 37 are provided at each side of these openings to receive and position a pair of closure panels 38 and 39, one for each opening. These panels are usually made from a single sheet of plywood and are held in place by turn buttons 40 which are pivoted on the battens.

In the normal working of the above mechanism, the motor 23 is started and, through the drive described, the head pulley 33 will lift the filled buckets of grain up from the pit hopper and this grain will be pitched out of each bucket, over the one in front, onto the bottom 21 of the head box as said buckets come over the head pulley. Accordingly, the grain slides theredown into the girber spout 22 and down the connected spout 13 to its destination. As the buckets are moving fairly fast in this pitching operation, it will be appreciated that considerable grain dust occurs in the head box, and as it has no means of escape, it is carried down the back leg by the empty buckets for later diffusion all over the elevator in a resulting health and fire hazard, as previously mentioned.

To correct the above bad condition the following changes are made in the above construction and these changes form part of the present invention: An opening 41 is provided through part of the rear portion of the cover of the head box 17 and a pipe 42 connects thereto, passes up through the roof 10 and terminates in a half-circle return elbow 43 for exhaust to atmosphere. A semi-circular opening 44, around the shaft 31, is cut in the closure panel 39, adjacent the chain sprocket 30, for air passage direct from the cupola into the head box at the head pulley.

The head pulley usually has six spokes 45 (see Figure 4 for the cross sectional shape) from its hub 46 to its rim 47. A series of six fan blades 48 (see Figure 5) and six fastening plates 49 (see Figure 6) are provided for at-

tachment thereto. The fan blade 48 is a zig-zag-shaped plate of metal having a rectangular-shaped central part 50 with triangular-shaped offset wings 51 and 52 on either side thereof, the pointed lower ends of the wings starting upward from the lower corners of the central part 50. Four holes 53 are provided in the central part 50, two at the upper corners thereof and two in the same position but half way down the fan blade. The wings are approximately a 45° angle from the central part 50 and all the upper edge of the fan blade (central part and both wings) is curved to conform with the interior edge of the wheel rim 47. The fastening plate 49 in Figure 6 is the same size and shape as the central part 50 of the fan blade and is provided with holes 54 therethrough which are the same size and will align with those 53 of said blade.

The object of the above fan blades 48 and fastening plates 49 is for the purpose of utilizing the central part of the head pulley as a fan when it is rotating. A fan blade 48 is centrally positioned against each of the wheel spokes 45 (see Figure 4) and a fastening plate 49 is aligned therewith on the opposite side of each spoke. Bolts 55 are then passed through the aligned holes 53 and 54 and tightened. The resulting wheel appears in face view as in Figure 3.

In operation, with the above changes, the attached fan blades 48 of the head pulley will draw air from the cupola, through the semi-circular opening 44, through the centre of the head pulley and be delivered against the closure panel 38 and into the head box to raise the pressure therein and so drive all grain dust up the pipe 42 for exhaust into the atmosphere, exterior of the elevator. Due to this cross movement of air against the panel 38, a turbulence is set up in the grain head which stirs up the dust, and in conjunction with the pressure, holds many fine particles in suspension for later exhaust out the pipe 42. In actual operation, the exterior of the cupola is completely enveloped by the exhausting dust. Very little of this dust, if any, goes into the bins or down the back leg with the empty buckets. Accordingly, the elevator can be kept relatively clean and the hazards to the health of workmen, or fire such as by an explosion due to a spark, is reduced to a minimum.

From the above disclosure it will be seen that the changes made are very slight in relation to the result achieved, merely consisting in the addition of the pipe 42, cutting the semi-circular opening 44 in the closure panel 39, and the attachment of the fan blades 48 and fastening plates 49 to the spokes of the head pulley. The changes are inexpensive while the benefit is considerable. It is contemplated, of course, to cast or mold the head pulley spokes integral with side wings such as shown at 51 and 52 as a better finished product for the purpose.

While in the present disclosure I have shown the head pulley operating as a fan, it will be appreciated that a separate power driven fan could be installed in one of the walls of the head box and the same result might be

achieved if both closure panels 38 and 39 were left intact and the other alterations used. Accordingly, I do not wish to be limited by details of construction except as specifically defined in the scope of the appended claims.

What I claim as my invention is:

1. In a grain elevator having a head box in the cupola thereof, said head box enclosing a drivable head pulley for belt elevating grain in an endless line of buckets to said head box and directing said grain to a girber spout; means for removing formed grain dust in said head box, comprising: a series of radial spokes between the hub and the rim of said head pulley and of an angular-shape in cross section to form fan blades within said head pulley; an opening in one side of said head box, around the drive shaft of said head pulley, for passage of air from said cupola into said head pulley and forcible delivery of same into said head box by the rotation of said spoke fan blades and for turbulence of said air therein; a pipe from the upper part of said head box for exhaust of said air therefrom.

2. In a grain elevator having a head box in the cupola thereof, said head box enclosing a drivable head pulley for belt elevating grain in an endless line of buckets to said head box and directing said grain to a girber spout; means for removing formed grain dust in said head box, comprising: a series of radial spokes between the hub and the rim of said head pulley; a series of fan blades of zig-zag-shape in cross section presenting a central longitudinal flat surface with offset angularly positioned wings on each side thereof; one of each of said fan blades centrally received against one side of each of said radial spokes and releasably secured thereto; an opening in one side of said head box, around the drive shaft of said head pulley, for passage of air from said cupola into said head pulley and forcible delivery of same into said head box by the rotation of said fan blades with and on the spokes of said head pulley for turbulence of said air therein and a pipe connecting the upper part of said head box for exhaust of said air therefrom.

3. In a grain elevator having a closed head box in the cupola thereof for receiving bucket elevated grain and directing same to a girber spout; means for removing formed grain dust from said head box, comprising: an opening in the side of said head box; a power drivable fan connected with said opening for forcibly propelling air from said cupola, into said head box to create a pressure therein; and a pipe from the upper part of said head box to atmosphere, for exhaust of said pressured air therefrom.
